FLUORESCENT LAMP ATTACHMENT FOR A LADDER

Joseph E. Senay, 1074 Banksville Road, Pittsburgh, Pa.

Filed Feb. 19, 1957, Ser. No. 641,129

11 Claims. (Cl. 248—201)

This invention relates to a fluorescent lamp attachment for a ladder and more particularly for an attachment which may be attached to the sidepiece of a ladder. In buildings, especially large office buildings having fluorescent lighting, it is necessary for a workman to spend a large proportion of his time changing burnt out lamps. For this purpose the workman usually has a hand truck on which he carries the lamps and a folding ladder. When he reaches the room where a lamp is burnt out he sets up his ladder, grasps a good lamp in one hand and then climbs the ladder, holding on with one hand. During this procedure it is not uncommon for the lamp to break. When the workman is in position to take out the lamp and replace it he experiences great difficulty since he only has one hand to handle each lamp. Because of the difficulties experienced in this procedure the workman often climbs the ladder with his hands free, takes out the burnt out lamp, climbs down, exchanges the burnt lamp with a good lamp and then climbs the ladder a second time. This, while safer, is a time-consuming operation. It is also necessary to take out the lamps periodically and clean them. This is also difficult because the hands are not free when climbing down with the dirty lamps or climbing up with clean lamps.

It is therefore an object of my invention to provide a fluorescent lamp attachment for a ladder which will permit a workman to remove or replace fluorescent lamps safely and expeditiously.

This and other objects will be more apparent after referring to the following specification and attached drawings, in which:

Figure 1 is a perspective view of a folding ladder with my attachment secured thereto;

Figure 2 is a perspective view of a clamp or bracket used at the top of the ladder;

Figure 3 is a view taken on the line III—III of Figure 2;

Figure 4 is a view taken on the line IV—IV of Figure 2;

Figure 5 is a perspective view showing two parts of the clamp of Figure 2 in assembled relationship;

Figure 6 is an exploded perspective view of part of the clamp of Figure 2;

Figure 7 is a perspective view of a slight modification of one member of the clamp of Figure 2;

Figure 8 is a perspective view of another embodiment of a clamp;

Figure 9 is a perspective view of a support at the lower part of the ladder; and

Figure 10 is a view, partly in section, of a modified support.

Referring more particularly to the drawings, reference numeral 2 indicates a folding ladder having the usual sidepieces 4 joined by steps 6. A clamp or bracket 8 is fastened to the outside of one of the sidepieces 4 adjacent the top thereof and a bottom support 10 is fastened to the outside of the same sidepiece 4 some dis-

tance below the clamp 8. One or more fluorescent lamps F are received in the clamp 8 and bottom support or socket 10. As shown in Figures 2 to 6 the clamp 8 is adjustable so that it can be fastened to a sidepiece 4 of various dimensions regardless of the material of which the sidepiece 4 is made. The clamp of Figures 2 to 6 comprises a front member 12, a pair of L-shaped intermediate members 14, two back members 16, and two spring jaws 18. The front member 12 has a stationary central jaw 20 fastened thereto and extending outwardly from the sidepiece 4. The outer end of jaw 20 has an enlarged portion 22 which may be formed by bending the end thereof as shown. The top and bottom sides of member 12 are bent rearwardly to form guides 24. A slot 26 is formed in member 12 on each side of jaw 20. Each of the jaws 18 has a flange 28 at its inner end with a hole 30 therein. The main portion of jaw 18 is concave on the side facing jaw 20 so that the distance between the jaws 18 and 20 at their outer ends is less than the distance therebetween a short distance from their outer ends. The extreme end 32 of the jaw 18 is bent outwardly away from jaw 20 so that the opening between jaws 18 and 20 is flared to better receive the lamp F. The jaws 18 and 20 may be coated with a plastic or rubber material to prevent scratching the lamps F. As shown in Figure 6 a rectangular nut 34 has a reduced width portion 36 which is readily received in slot 26 but which cannot turn therein. In assembling each of the jaws 18 on the member 12 the nut 34 is abutted against the rearward side of member 12 with its reduced portion 36 passing through slot 26 and hole 30 and a screw 38 with a washer 40 thereon is threaded into nut 34. Each of the L-shaped members 14 has a rearwardly extending leg 42 with a threaded hole 44 therein and two spaced apart legs 46 adapted to be received in guides 24. Each of the members 16 has a forwardly extending leg 48, a rearwardly extending leg 50 with a threaded hole 52 therein, and a connecting portion 54 parallel to member 12. If desired, only one of the holes 52 need be threaded. Each of the legs 48 has top and bottom flanges 56 extending toward the other leg 48 and a longitudinal slot 58 between the flanges 56.

In assembly the jaws 18 are fastened to the member 12 as described above and the legs 46 are slid into guides 24 after which the parts are placed over sidepiece 4. The members 16 are then positioned from the inside of the sidepiece 4 with the flanges 56 receiving the legs 42. A screw 60 is passed through each of the slots 58 and threaded into hole 44. A screw 62 is then threaded into holes 52 and drawn up tight to lock the clamp in the desired position on the sidepiece 4. The telescoping relationship of the members 14 in the member 12 enables the clamp to be adjusted for various widths of sidepieces 4 and the telescoping relationship of members 14 and 16 enables the clamp to be adjusted for various thicknesses of sidepieces 4. The jaws 18 may be moved toward and away from jaw 20 and locked in place so that lamps F of various diameters may be securely held.

Instead of having two intermediate members 14 a front member 12' may be provided having a rearwardly extending leg 42' as shown in Figure 7. This member 12' takes the place of front member 12 and one of the intermediate members 14 with the leg 42' corresponding to leg 42 of member 14. The construction and operation of the clamp is otherwise the same as in the first embodiment.

Figure 8 shows a clamp 8' which is much simpler in construction than clamp 8 but which is not adjustable for various sizes of lamps. The clamp 8' consists of two outer jaws 18' and a central jaw 20' which are of the same general construction as jaws 18 and 20. As shown the clamp 8' is made of a single piece of material, prefer-

ably spring-like metal, with the central jaw 20' being formed of two legs 64 of the material. A screw or rivet 66 may be passed through holes in the legs 64 to hold them closely together. The jaws 18' and 20' are connected by portions 68 having holes 70 therein. In assembling the clamp 8' on a ladder, holes may be drilled in the sidepiece 4 at the desired position and bolts passed therethrough and through holes 70 to lock the clamp in place. Where the sidepiece is made of wood a wood screw may be passed through each of the holes 70 and threaded into the wood.

As shown in Figure 9 the bottom support 10 consists of two sockets 72 each having an inverted conical lower portion 74 and a cylindrical upper portion 76. A pair of spaced apart flanges 78 are fastened to the outside of the upper portion 76 for receiving a strap 80 which has flanges 82 at its ends. The flanges 82 abut against the sidepiece 4 and have openings therein for receiving screws 84 which are threaded into the sidepiece. If the sidepiece 4 is not made of wood holes may be drilled in the sidepiece 4 for receiving bolts.

Figure 10 shows a second embodiment of a socket which may be used. In this embodiment there is a cylindrical outer portion 86 spaced from and attached to an inverted conical member 88 so as to provide a seat 90 for a spring 92. A cylindrical member 94 has a closed bottom which provides a second seat for the spring 92 and a flange 96 at its upper end which is bent inwardly after the member 88 is placed in the cylinder. A U-shaped member or channel 98 may be fastened to the outside of cylinder 94 for receiving the strap 80.

With the members 8 and 10 fastened to the sidepiece 4 in the desired position the workman can place one or two lamps F in the bottom sockets and force the jaws 18 and 20 apart to receive the upper part of the lamps F and grip them to prevent outward movement thereof. His hands are then free while he climbs the ladder and removes the burnt out lamp. If only one lamp is in the attachment he may place the burnt out lamp therein and have both hands free to take out the good lamp and place it in the ceiling socket. Otherwise he must hold the burnt out lamp in one hand and pull out a good one.

While it is preferred to have the arrangement shown the top clamp could be closed rather than open. In this case the workman would pull the lamp upwardly rather than outwardly. With the socket shown in Figure 10 it is possible to use a socket, such as shown in Figure 9, in upside down position in place of clamp 8. This is possible since the spring 92 permits the socket 88 to be pushed downwardly with the lamp F so that the upper part of the lamp F can be positioned below the bottom of the upper socket and then raised when the spring 92 expands.

While several embodiments of my invention have been shown and described it will be apparent that other adaptations and modifications may be made without departing from the scope of the following claims.

I claim:

1. In combination with a ladder having a sidepiece, a bottom support attached to said sidepiece a considerable distance from the top thereof, said bottom support having a pair of inverted conical sockets for receiving one end of fluorescent lamps, and a top bracket attached to said sidepiece above said bottom support, said top bracket including a center jaw and a pair of resilient curved side jaws one on each side of said center jaw, the maximum distance between the center jaw and each side jaw being only slightly greater than the diameter of said lamps and the distance between the center jaw and each side jaw at their forward ends being less than the diameter of said fluorescent lamps whereby the upper end of said fluorescent lamps may be gripped between the jaws.

2. In combination with a ladder having a sidepiece, a bottom support attached to said sidepiece a considerable distance from the top thereof, said bottom support having

a pair of inverted conical sockets for receiving one end of fluorescent lamps, and a top bracket attached to said sidepiece above said bottom support, said top bracket including means for attaching said bracket to said sidepiece, a center jaw and a pair of resilient curved side jaws mounted for movement toward and away from said center jaw one on each side of said center jaw, the maximum distance between the center jaw and each side jaw being only slightly greater than the diameter of said lamps and the distance between the center jaw and each side jaw at their forward ends being less than the diameter of said fluorescent lamps whereby the upper end of said fluorescent lamps may be gripped between the jaws.

3. In combination with a ladder having a sidepiece, a bottom support attached to said sidepiece a considerable distance from the top thereof, said bottom support having a pair of inverted conical sockets for receiving one end of fluorescent lamps, said sockets being slidably mounted in said support, resilient means for urging said sockets upwardly, and a top bracket attached to said sidepiece above said bottom support, said bracket including a center jaw and a pair of resilient curved side jaws one on each side of said center jaw, the maximum distance between the center jaw and each side jaw being only slightly greater than the diameter of said lamps and the distance between the center jaw and each side jaw at their forward ends being less than the diameter of said fluorescent lamps whereby the upper end of said fluorescent lamps may be gripped between the jaws.

4. In combination with a ladder having a sidepiece, a bottom support attached to said sidepiece a considerable distance from the top thereof, said bottom support having a pair of inverted conical sockets for receiving one end of fluorescent lamps, said sockets being slidably mounted in said support, resilient means for urging said sockets upwardly, and a top bracket attached to said sidepiece above said bottom support, said top bracket including means for attaching said bracket to said sidepiece, a center jaw and a pair of resilient curved side jaws mounted for movement toward and away from said center jaw one on each side of said center jaw, the maximum distance between the center jaw and each side jaw being only slightly greater than the diameter of said lamps and the distance between the center jaw and each side jaw at their forward ends being less than the diameter of said fluorescent lamps whereby the upper end of said fluorescent lamps may be gripped between the jaws.

5. In combination with a ladder having a sidepiece, a bottom support attached to said sidepiece a considerable distance from the top thereof, said bottom support having an inverted conical socket for receiving one end of a fluorescent lamp, and a top bracket attached to said sidepiece above said bottom support, said top bracket including a pair of jaws, at least one of said jaws being resilient and curved, the maximum distance between the jaws being only slightly greater than the diameter of said lamps and the distance between said jaws at their forward ends being less than the diameter of said fluorescent lamp whereby the upper end of said fluorescent lamp may be gripped between said jaws.

6. In combination with a ladder having a sidepiece, a bottom support attached to said sidepiece a considerable distance from the top thereof, said bottom support having an inverted conical socket for receiving one end of a fluorescent lamp, and a top bracket attached to said sidepiece above said bottom support, said top bracket including a front member, an L-shaped intermediate member slidably mounted on said front member with one side thereof extending rearwardly, an L-shaped back member having one end slidably mounted on said intermediate member at right angles to the slidable movement of said intermediate member, means for fastening the other end of said back member to said front member, said front, intermediate and back members gripping said sidepiece therebetween, and a pair of jaws mounted on

said front member, at least one of said jaws being resilient and curved, the maximum distance between the jaws being only slightly greater than the diameter of said lamps and the distance between said jaws at their forward ends being less than the diameter of said fluorescent lamp whereby the upper end of said fluorescent lamp may be gripped between said jaws.

7. In combination with a ladder having a sidepiece, a bottom support attached to said sidepiece a considerable distance from the top thereof, said bottom support having a pair of inverted conical sockets for receiving one end of fluorescent lamps, said sockets being slidably mounted in said support, resilient means for urging said sockets upwardly and a top bracket attached to said sidepiece above said bottom support, said top bracket including a front member, an L-shaped intermediate member slidably mounted on said front member with one side thereof extending rearwardly, an L-shaped back member having one end slidably mounted on said intermediate member at right angles to the slideable movement of said intermediate member, means for fastening the other end of said back member to said front member, and a pair of resilient side jaws adjustably mounted on said front piece one on each side of said center jaw, the distance between the center jaw and each side jaw at their forward ends being less than the diameter of said fluorescent lamps whereby the upper ends of said fluorescent lamps may be gripped between the jaws.

8. In combination with a structure having a side piece, a bracket for supporting a pair of tubular members, said bracket including a front member, an L-shaped intermediate member slidably mounted on said front member with one side thereof extending rearwardly, an L-shaped back member having one end slidably mounted on said intermediate member at right angles to the slideable movement of said intermediate member, means for fastening the other end of said back member to said front member, said front, intermediate and back members gripping said side piece therebetween, and a pair of resilient jaws mounted on said front member, the distance between said jaws at their forward ends being less than the diameter of said tubular member whereby the tubular member may be gripped between said jaws.

9. In combination with a structure having a side piece, a bracket for supporting a pair of tubular members, said bracket including a front member, an L-shaped intermediate member slidably mounted on said front member with one side thereof extending rearwardly, an L-shaped back member having one end slidably mounted on said intermediate member at right angles to the slideable movement of said intermediate member, means for fastening the other end of said back member to said front member, said front, intermediate and back members gripping said side piece therebetween, a center jaw

5 mounted on said front member, and a pair of resilient side jaws adjustably mounted on said front piece one on each side of said center jaw, the distance between the center jaw and each side jaw at their forward ends being less than the diameter of said tubular members whereby the tubular members may be gripped between the jaws.

10. In combination with a ladder having a sidepiece, a bottom support attached to said sidepiece a considerable distance from the top thereof, said bottom support including two fluorescent lamp receiving sockets, each of said sockets having its upper portion of such dimensions as to readily receive one end of a fluorescent lamp and a lower portion of lesser dimensions to limit the downward movement of said lamp, and a top bracket attached to said sidepiece above said bottom support, said top bracket including a center jaw and a pair of curved resilient side jaws one on each side of said center jaw, the maximum distance between the center jaw and each side jaw being only slightly greater than the diameter of said lamps and the distance between the center jaw and each side jaw at their forward ends being less than the diameter of said fluorescent lamps whereby the upper end of said fluorescent lamps may be gripped between the jaws.

15 20 25 30 35 40 45 50

11. In combination with a ladder having a sidepiece, a bottom support attached to said sidepiece a considerable distance from the top thereof, said bottom support having its upper portion of such dimensions as to readily receive one end of a fluorescent lamp and a lower portion of lesser dimensions to limit the downward movement of said lamp, and a top bracket attached to said sidepiece above said bottom support, said top bracket including a pair of jaws, at least one of said jaws being resilient and curved, the maximum distance between the jaws being only slightly greater than the diameter of said lamps and the distance between said jaws at their forward ends being less than the diameter of said fluorescent lamp whereby the upper end of said fluorescent lamp may be gripped between said jaws.
